WILLIAM F. EAMES, OF EDGEWOOD, PENNSYLVANIA, ASSIGNOR TO WESTINGHOUSE ELECTRIC & MANUFACTURING COMPANY, A CORPORATION OF PENNSYLVANIA

ELEVATOR CONTROL SYSTEM

Application filed January 20, 1930. Serial No. 421,981.

My invention relates to systems of elevator control and more particularly to systems of control for elevators wherein the selective directional control is effected by means of single up and down push buttons mounted within the elevator car.

In department stores and other buildings where the floor-to-floor traffic is comparatively heavy, an elevator car, in making a trip from one to the other of the terminal floors, is usually required to come to a stop at each of the intermediate floors. It frequently happens, however, by reason of unusual traffic conditions on one or more of the floors, or related causes, that it becomes desirable for the elevator car to proceed past certain of the floors on a given trip without stopping.

I am aware that the prior art has produced elevator-control systems of the general type contemplated by my invention but all of such types with which I am familiar have certain limitations which I propose to overcome and which I shall outline generally in the following paragraphs.

Recent developments in elevator systems have given rise to driving means capable of driving the elevator car at speeds greater than the speed which may be accelerated to, and decelerated from, in the course of travel between two adjacent floors of a building. Obviously, the elevator system is most efficiently operated when such higher speeds are utilized.

Therefore, in the applications which I now find most suitable in which to practice my invention, two conditions of operation exist, which are, first, the condition in which the car is required to stop at each floor, and in which the speed is, therefore, limited to a speed which may be accelerated to, and decelerated from, in the course of the one-floor run, and, second, the condition in which certain of the floors are to be bypassed, and in which it is, therefore, permissible to operate the car at a higher speed.

The systems of the prior art, while permitting the bypassing of certain of the floors, have limited the elevator speed on the longer runs to the lower speed utilized on the one-floor runs, or, if the possibility of higher

speeds have been provided, such provision has been made at the expense of additional controlling means within the elevator car.

My invention, however, contemplates a system of circuits whereby a single set of up and down push buttons within the elevator car may be selectively operated to provide the higher speed for the longer runs and the lower speed for the one-floor runs.

It is an object of my invention, therefore, to provide an elevator system of the type wherein momentary actuation of the control means is effective to cause the car to start toward, run to and stop at, the floor next approached, and wherein a sustained actuation of the control means is effective to cause the car to start, and run for a distance greater than the distance between two adjacent floors.

Another object of my invention is to provide a system of the above-specified type wherein a sustained actuation of the control means is effective to cause the car to make the extended run at a greater speed than the speed attained on the one-floor run.

Another object of my invention is to provide an elevator-control system of the above type wherein the car is caused to travel at such increased speed as long as the control means are maintained in its actuated position.

My invention will be described in the following specification, for a better understanding of which reference may be had to the accompanying sheet of drawing, in which the sole figure is a wiring diagram illustrating what I now consider to be a preferred circuit arrangement by which to practice my invention.

Referring to the drawing, I have illustrated an elevator car C suspended in the usual manner by means of a hoisting cable Ca which passes over, and is driven by, a hoisting drum D, and to the other end of which is attached a suitable counterweight Cw.

I have illustrated the motive means for the elevator car C as being of the Ward-Leonard or variable-voltage type, which comprises a driving motor M having an armature M' and a shunt field winding MF, illustrated

herein as connected, for constant energization, across the line conductors L1 and L2 and which is directly connected to, and drives, the armature G' of a generator G. The generator G is of the compound-wound type having a series field winding GSF, a separately excited field winding GF, and a demagnetizing winding GAF. The voltage output of the generator G is applied directly, by way of a local circuit, to the terminals of the armature EM' of the elevator hoisting motor EM, which is provided with a separately excited field winding EMF illustrated as connected, for constant energization, across the line conductors L1 and L2, and which is directly connected to, and drives, the hoisting drum D.

The speed and direction of rotation of the elevator motor EM is suitably controlled by varying the direction and value of the output voltage of the generator G, which, in turn, is controlled by varying the value and direction of excitation voltage supplied to the separately excited generator field winding GF. As will be later described in detail, this latter variation is effected by means of suitable up-and-down-direction switches 1 and 2, their associated direction relays 8 and 9, and the accelerating relays 3, 4 and 5, which are controlled from the elevator car by means of the up and down car buttons U and D.

To insure that the car may be stopped accurately level with each landing, I have provided an automatic landing system of the inductor type, representative forms of which are illustrated and described in detail in the copending applications of Edgar M. Bouton, Serial Number 731,921, filed August 14, 1924, and Harold W. Williams and Danilo Santini, Serial Number 279,771, filed May 22, 1928, both of which are assigned to the Westinghouse Electric and Manufacturing Company.

As described therein, an inductor landing system comprises a plurality of inductor relays, one for each step of deceleration employed in bringing the elevator motor from full speed to zero speed. Each of the inductor relays comprises a pair of independently movable armature members upon which is mounted a single energizable coil, which, when energized, is normally ineffective to actuate either of the armature members to engage, or cause to be disengaged, the contact members controlled thereby. However, when a magnetizable plate is brought adjacent to either of the movable armature members, a magnetic path of reduced reluctance is provided for that portion of the flux generated by the coil which passes through that armature member, by reason of which, such armature member is actuated to engage, or to be disengaged from the contact members controlled thereby. A similar plate brought adjacent to the other armature member when

the coil is energized, will, of course, result in the actuation of that armature member.

In the applications referred to, one of the two armature members is effective to interrupt circuits employed during car travel in the up direction and the other is effective to interrupt circuits employed during car travel in the down direction. In practicing my invention, I employ the inductor relays to control three steps of deceleration, and have, therefore, provided an intermediate-speed inductor relay IL, having armatures ILU and ILD, for the up and down directions, respectively; slow-speed inductor relay SL, having armatures SLU and SLD for the up and down directions, respectively, and a stopping inductor relay SR, having armatures SRU and SRD for the up and down directions, respectively. Associated with armatures ILU, SLU and SRU are groups of inductor plates ILU', SLU', and SRU', one group for each floor, and mounted stationarily in the elevator hatchway. Similarly, groups of inductor plates ILD', SLD', and SRD', one group for each floor, perform a similar function when the car is traveling in the down direction.

Upon actuation of the starting means to cause the car to operate in either direction, the holding circuits for the accelerating and the associated direction switch are maintained through the normally closed contact members of the proper inductor relay armatures. As the car, in its movement through the shaft, passes the inductor plates which are stationarily mounted in the hatchway at a predetermined spacing in advance of each floor, the inductor relays are actuated to sequentially deenergize the accelerating relays and the associated direction switch to thereby bring the car to rest accurately level with the floor landing.

As will be more apparent from the following description, the inductor relay armatures ILU and ILD are effective to control the intermediate-speed accelerating relay 4, the inductor relay armatures SLU and SLD are effective to control the slow-speed-accelerating relay 3 and the inductor relay armatures SRU and SRD are effective to control the up-and-down-direction switches 1 and 2, while no inductor relay is provided for the high-speed accelerating relay 5, which is placed under the control of a voltage relay 7 the operation of which may best be understood by reference to an assumed operation. The operation of relay TL, which controls the circuit to the coils of the inductor relays, when decelerating from high speed, may also best be understood by reference to an assumed operation.

Assuming that it is desired to move the elevator car upwardly, the operator thereof may actuate the car button U to complete a circuit to the up-direction relay 8 and the stop con-

trol relay 6, which extends from line conductor L1, through conductor 12, the coil of stop control relay 6, conductors 13 and 14, the now closed contact members of up button U, conductor 15, the coil of up-direction relay 8, and conductors 16, 17 and 18, to line conductor L2.

Upon being energized, the stop control relay 6 is actuated to close its contact members *a* to partially complete a circuit to the high-speed accelerating relay 5, the function of which will be later described, and opens its normally closed contact members *b* to interrupt the circuit to the coils of the various inductor relays, thereby rendering these devices ineffective to control the operation of the elevator system.

Upon being energized, up-direction relay 8 closes its contact members *a* to complete a circuit to the up-direction switch 1, which circuit extends from line conductor L1, through conductors 19 and 20, the contact members *a* of relay 8, conductor 21, the coil of up-direction switch 1, and conductors 22, 23 and 18, to line conductor L2.

Upon being energized, up-direction switch 1 is actuated to close its contact members *a*, *b*, *c*, *d*, *e* and *f*, and to open its contact members *g*. The closing of contact members *a* of up-direction switch 1 completes a circuit for the coil of this switch which is independent of the position of the button U and which places this switch under the control of the stopping inductor relay SR. This circuit extends from line conductor L1, through conductors 24, 25 and 26, the contact members 27 of inductor relay SR controlled by up-direction armature SRU, conductor 28, the contact members *a* of up-direction switch 1, conductor 29 and the coil of up-direction switch 1 and thence to line conductor L2, as previously traced.

The closing of contact members *b* and *c* of up-direction switch 1 completes a circuit to the separately excited generator field winding GF, which extends from line conductor L1, through conductor 19, the now closed contact members *b* of up-direction switch 1, conductors 30 and 31, the separately excited field winding GF, conductors 32 and 33, the contact members *c* of up-direction switch 1, conductor 34, the resistor R and conductor 35, to line conductor L2.

Now being supplied with field excitation of a predetermined value and direction, the voltage output of the generator G rises to such value as to cause the elevator motor EM to drive the car upwardly at landing speed.

The closing of contact members *d* of up-direction switch 1 completes a circuit to the coil of slow-speed accelerating relay 3, which extends from line conductor L1, through conductors 24, 25 and 36, the contact members 37 of relay SL, controlled by up-direction armature SLU, conductor 38, the contact

members *d* of up-direction switch 1, conductors 39 and 40, the coil of accelerating relay 3, and conductor 41, to line conductor L2.

Upon being energized, relay 3 is actuated to close its contact members *a* to exclude a portion of the resistor R from the circuit of the separately excited field winding GF, by way of conductors 42 and 43, the contact members *a* of relay 3 and conductors 44 and 45. The reduction in field-circuit resistance causes the generator voltage to increase a predetermined amount, and the elevator motor, consequently, to accelerate.

The closing of contact members *e* of up-direction switch 1 completes a circuit to the coil of intermediate speed accelerating relay 4, which extends from line conductor L1, through conductors 24, 25 and 46, the contact members 47 of intermediate-speed inductor relay IL controlled by up-direction armature ILU, conductor 48, contact members *e* of up-direction switch 1, conductors 49 and 50, the coil of accelerating relay 4 and conductor 41, to line conductor L2.

Upon being energized, relay 4 is actuated to close its contact members *a* to exclude another portion of resistor R from the circuit of the separately excited generator field winding GF by way of conductors 45 and 44, the contact members *a* of relay 4 and conductor 53. The increase in generator excitation caused thereby results in the acceleration of the elevator motor to its intermediate running speed.

It will be observed that the accelerating relays 3 and 4 are provided with dash-pot retarding devices D3 and D4, and that these relays are not actuated immediately upon completion of their circuits. It will be understood that the time delay provided may be varied between wide limits, in accordance with the adjustment of the dash-pot device. In practice, I delay the sequential action of the relays until such time as the voltage of the generator has risen almost to the value determined by the resistance then in the circuit of the separately excited generator field winding. By so doing, I obtain an acceleration curve for the elevator car best suited to the comfort of the passengers and the efficiency of the system.

It will be noted that the circuits to the up-direction switch 1 and the accelerating relays 3 and 4 are now independent of the car button U and of the relay 8, and that, in order to accelerate the car to the intermediate running speed, this button need be only momentarily actuated.

The stop control relay 6, (which controls the energization of the coils of the inductor relays, as hereinbefore described,) is directly under the control of the car buttons U and D. As long, therefore, as the operator maintains the button U in the actuated position,

the inductor relays are ineffective to cause deceleration of the car which will, therefore, proceed up or down the elevator shaft without stopping.

5 If, however, the operator desires to stop the elevator car at the floor adjacent to the starting floor, he may actuate the button U only momentarily, and, by so doing, render the inductor relays effective to stop the car at 10 such next floor.

Assuming that the operator does release the car button U after having initiated motion of the car, the circuit to the stop control relay 6 is interrupted, which relay, therefore,

15 opens its contact members *a* to interrupt the circuit of relay 8, and recloses its contact members *b*. The closing of contact members *b* completes a circuit to the coil of intermediate-speed inductor relay IL, which circuit 20 extends from line conductor L1, through conductors 19, 54 and 55, the contact members *f* of up-direction switch 1, conductors 56, 57 and 58, the coil of inductor relay IL, conductors 59 and 60, the normally closed contact 25 members *a* of relay TL, conductor 61, the normally closed contact members *b* of stop control relay 6 and conductor 18, to line conductor L2.

As the car, in its upward movement, passes 30 the inductor plate ILU', the armature ILU of relay IL is actuated to open its contact members 47, thereby interrupting the circuit to the intermediate-speed accelerating relay 4. Upon being deenergized, relay 4 rein-

35 serts a portion of the resistor R into the circuit of the separately excited generator field winding GF to thereby reduce the generator voltage and, consequently, the elevator motor speed.

40 Upon being deenergized, relay 4 closes its contact members *b* to complete a circuit to the coils of inductor relays SL and SR, which circuit extends, as traced for the coil of relay IL, through conductor 57, thence, in parallel 45 relation, through the coils of relays SL and SR, conductor 62, the normally closed contact members *b* of relay 4 and conductor 64, and thence to line conductor L2, as previously traced for the coil of relay IL.

50 It will be noted, therefore, that the car button U must be released prior to the time that the relay IL passes the associated inductor plate ILU' if the inductor relays are to be rendered effective to cause the car to 55 come to a stop at the floor next approached. If the button U is maintained in the actuated position until after the relay IL passes the inductor plate ILU', it will be understood that the car will proceed past the next floor 60 but will be brought to a stop at the first floor after such next floor.

As the car in its upward movement brings the inductor relay SL adjacent to the associated inductor plate ILU', the armature 65 SLU of this relay is actuated to open its con-

tact members 37 to thereby interrupt the circuit to the coil of the accelerating relay 3.

Upon being deenergized, accelerating relay 3 opens its contact members *a* to reinsert the remaining portion of resistor R in the circuit of the winding GF, thereby reducing the generator voltage and causing the elevator motor EM to decelerate to its landing speed.

Similarly, as the inductor relay SR is brought adjacent to the associated inductor plate SRU', the contact members 27 thereof are actuated to open position to interrupt the circuit to the coil of up-direction switch 1.

Upon being deenergized, up-direction switch 1 interrupts the circuit to the separately excited generator field winding GF, and completes a circuit to the demagnetizing winding GAF, extending from one terminal of the generator G, through the winding GAF, conductor 75, the normally closed contact members *g* of up-direction switch 1, conductor 76, the normally closed contact members *g* of down-direction switch 2, and conductor 77, to the opposite terminal of the generator G.

The demagnetizing winding GAF is so wound and mounted upon the generator G as to oppose, and quickly reduce to zero, the residual magnetism of the generator.

For purposes of simplicity, I have not illustrated the usual magnetic brake which is employed to bring the car quickly to rest upon the deenergization of the direction switch.

Upon deenergization of the up-direction switch 1, therefore, the car is quickly brought to rest at the landing, at which time the operator may open the door to admit or discharge passengers.

My invention, as thus far described, provides an elevator-control system well suited for use in department stores or buildings wherein it is desired to stop the car at each floor in a given trip in either direction.

As hereinbefore noted, however, there may be times at which it is desirable to proceed past certain of the floors without stopping thereat, and, in such instances, it is highly desirable that the elevator car can be caused 111 to accelerate to, and run at, a higher speed than is attainable on the one-floor runs.

I have, therefore, provided means whereby, if the car button is maintained in the actuated position longer than a predetermined time, the elevator motor is caused to accelerate to a higher speed, and to run at such speed as long as the car button is maintained in the actuated position. I shall refer, in the claims, to such high-speed operation 125 as being responsive to a "sustained actuation" of the control devices U and D.

The means to accomplish this result may be made responsive to any suitable timing mechanism. Since the rise of generator volt-

age upon application of field excitation is directly proportional to the time during which the excitation is applied (until the maximum voltage is reached), I now find 5 that a relay connected across the terminals of the generator constitutes a convenient method of attaining my object.

I have illustrated, therefore, a relay 7, the coil of which is connected directly across 10 the terminals of the generator by way of conductors 78 and 79. I now find it desirable to design the relay 7 to be operably responsive to a generator voltage just slightly lower than a generator voltage corresponding 15 to the intermediate running speed of the elevator motor. By so arranging the device, it will be seen that the operator, by releasing the car button U or D at any time before the elevator attains its intermediate running speed, may cause the elevator car to 20 make a stop at the floor adjacent to the starting floor; and that, by maintaining the car button in its actuated position a longer time, i. e., by providing a "sustained actuation", 25 may cause the car to accelerate to, and run at, its high speed.

Assuming, therefore, that, upon starting, the operator does maintain the car button U in the actuated condition longer than this 30 predetermined interval, or until the voltage of the generator G rises to a value sufficiently high to actuate the voltage relay 7, a circuit is completed for the coil of the high-speed accelerating relay 5, which circuit extends 35 from line conductor L1, through conductor 11, the contact members *a* of relay 6 (which it will be remembered are closed since the car button U is in the actuated position), conductor 65, the now closed contact members *a* 40 of relay 7 and conductor 66, a junction point 67, conductor 68, the coil of accelerating relay 5 and conductors 69 and 70, to line conductor L2.

The closing of contact members *a* of relay 45 5 excludes the remaining portion of resistor R from the circuit of the separately excited generator field winding GF by way of conductor 71, contact members *a* of relay 5 and conductor 43. The excitation of the generator G is, therefore, increased to a maximum, 50 and the elevator motor is caused to accelerate to, and run at, its high speed.

The closing of contact members *a* of relay 7 also completes a circuit to the coil of the 55 relay TL, which circuit extends from line conductor L1 to the junction point 67, as previously traced, thence, through conductor 72, the coil of relay TL and conductor 70, to line conductor L2. The relay TL is provided 60 with a dash-pot arrangement whereby, upon deenergization, a definite time elapses prior to the closing of the contact members thereof. The object of this provision will be made apparent in a following paragraph.

65 As the elevator car approaches a floor at

which it is desired to make a stop, the operator may release the button U to deenergize the stop control relay 6 which, in turn, deenergizes the relay 5 and causes the elevator motor to decelerate to its normal or intermediate running speed.

The opening of the contact members *a* of relay 6 also interrupts the circuit to the coil of the relay TL, but, as described, the contact members *a* of this relay are not immediately closed by reason of the dashpot device associated therewith.

Until such time as the contact members *a* of the relay TL are closed, the inductor relays are ineffective to cause slow down and stopping of the car since the circuits to the coils of these relays are led therethrough.

The time delay in the closing of the contact members *a* of the relay TL is determined by the time the elevator motor requires in 85 decelerating from the high speed to the intermediate speed, it being, of course, undesirable that the relay ILU should be permitted to deenergize the relay 4 prior to the time at which the motor has decelerated to a 90 speed slightly in excess of the intermediate speed.

If, therefore, the operator releases the button U when the elevator car is at a distance in 95 advance of the inductor plate ILU' less than the distance moved by the car while the elevator motor is decelerating from high speed to intermediate speed, the inductor relay IL will be rendered ineffective to cause the car to decelerate to its slow speed. Under these 100 conditions then, the car will proceed past that floor and will be brought to a stop at the next floor approached.

Since operation in the down direction is in 105 all respects similar to operation in the up direction, with the exception that the down car button D, the down-direction switch 2, and the inductor relay armatures ILD, SLD and SRD replace the up car button U, the up-direction which 1, and the inductor relay 110 armatures ILU, SLU and SRU, it is not believed that a detailed description thereof is necessary.

It will be seen, therefore, that I have provided an elevator-control system adapted for 115 intermediate-speed service wherein stops are made at each floor and which is also adapted to be operated at a higher speed in the event that certain of the floors do not require the services of the car. It will be also noted that I 120 have provided these two features of operation without the addition of additional control means within the elevator car C and have so arranged the system that the selective operation is obtained by merely actuating a 125 single control device for a longer or a shorter period.

Since modifications of my invention will be apparent to those skilled in the art and since the present embodiment of my inven- 130

tion is merely illustrative, I do not wish to be limited to the details thereof except as defined in the appended claims.

I claim as my invention:

5. 1. In an elevator control system, an elevator, motive means therefor, a control device actuatable to a single circuit-closing position, intermediate-speed control means for said motive means operably responsive to a 10 momentary actuation of said control device, a self-holding circuit for said intermediate-speed control means independent of said control device, stopping means for said motive means effective only when said control 15 device is released and interposed in said self-holding circuit, high-speed control means for said motive means operably responsive to a sustained actuation of said control device, and means effective after actuation of said 20 high-speed control means to render said stopping means ineffective for a predetermined time after said control device is released.

2. In an elevator-control system, an elevator, operable past a plurality of floors, motive means therefor, control means for said motive means effective to cause said elevator to travel only the distance between adjacent floors, control means for said motive 30 means effective to cause said elevator to travel a greater distance, a control device actuatable to a single circuit-closing position for rendering both of said control means effective, and means dependent upon the length of time said 35 control device is actuated to determine which of said control means is to be effective.

3. In an elevator-control system, an elevator operable past a plurality of floors, motive means for said elevator, a control device actuatable from a normal to a single circuit-closing position, intermediate-speed control means for said motive means operably responsive to a momentary actuation of said control device, high-speed control means for said motive 45 means operably responsive to a sustained actuation of said control device, stopping means for said motive means effective only when said control device is in said normal position and operably responsive to the actuated 50 condition of said intermediate-speed control means to stop said elevator at the next floor approached by said elevator, and means operably responsive to the actuation of said high-speed means to render said 55 stopping means ineffective at said next floor.

4. In an elevator-control system, an elevator operable past a floor, motive means for said elevator, a control device actuatable from a normal to a single circuit-closing position, 60 control means for said motive means operably responsive to a momentary actuation of said control device to cause said elevator to travel the distance between two floors, control means for said motive means operably responsive to a sustained actuation of said control de-

vice to cause said elevator to travel while said control device is actuated, and means effective after said last named means has been actuated to continue the travel of said car a predetermined time after said control device is returned to said normal position.

5. In an elevator-control system, an elevator operable past a plurality of floors, motive means for said elevator, means for stopping said elevator at said floors, means for starting said elevator comprising a control device actuatable from a normal to a single circuit-closing position, means operably responsive to a momentary actuation of said control device to cause said car to travel at an intermediate speed subject to the stopping means at the next floor approached by said elevator, and means operably responsive to a sustained actuated condition of said control device to cause said elevator to travel at a higher speed subject to none of said stopping means.

In testimony whereof, I have hereunto subscribed my name this 15th day of January, 1930.

WILLIAM F. EAMES.
